UNITED STATES PATENT OFFICE.

CHARLES E. JAQUES, OF OAKPARK, ILLINOIS.

DESIGN FOR AN ADVERTISING PUZZLE-SHEET.

SPECIFICATION forming part of Design No. 35,568, dated January 7, 1902.

Application filed December 13, 1901. Serial No. 85,858. Term of patent 7 years.

To all whom it may concern:

Be it known that I, CHARLES E. JAQUES, a citizen of the United States, residing at Oak-
park, in the county of Cook and State of Illi-
nois, have invented and produced a new and
original Design for Advertising Puzzle-
Sheets; and I do hereby declare the following
to be a full, clear, and exact description of
the same, reference being had to the accom-
panying description, forming a part thereof.

My invention relates to advertising puzzle-
sheets; and my object is to produce a design
arranged with pattern of a puzzle and space
arranged about the pattern adapted for
printed matter, such as advertisements and
a description of the puzzle.

The drawing forming a part of this specifi-
cation shows a plan view of my design, the
leading feature of which is composed of four
T-shaped patterns arranged in pairs, with a
space between each pair, the patterns being
each divided into squares which, except the

bottom square of each pattern, contain one of
a series of four figures.

A A A A denote the four patterns, arranged 25
in pairs, with a space B between each pair.
The vertical portions of each pair of patterns
are arranged parallel in juxtaposition.

C denotes the squares, separated by dotted
lines c, containing figures of cans D. 30

E E denote blank spaces upon each side.

The spaces B and E E are adapted for ad-
vertisements and directions for the puzzle.

Having described my invention, what I
claim as new, and desire to secure by Letters 35
Patent, is—

The design for an advertising puzzle-sheet
as herein shown and described.

In testimony whereof I affix my signature
in presence of two witnesses.

CHARLES E. JAQUES.
